US00D944101S

(12) **United States Design Patent** (10) **Patent No.:** **US D944,101 S**
(45) **Date of Patent:** **** Feb. 22, 2022**

(54) **HANDHELD DEVICE**

(71) Applicant: **Teledyne FLIR Detection, Inc.**,
Stillwater, OK (US)

(72) Inventor: **Steve W. Fleetwood**, Oak Ridge, TN
(US)

(73) Assignee: **Teledyne FLIR Detection, Inc.**,
Stillwater, OK (US)

(**) Term: **15 Years**

(21) Appl. No.: **29/709,539**

(22) Filed: **Oct. 15, 2019**

(51) LOC (13) Cl. **10-04**

(52) U.S. Cl.

USPC **D10/47; D10/78; D10/81**

(58) **Field of Classification Search**

(57) **CLAIM**

The ornamental design for a handheld device, as shown and described.

DESCRIPTION

FIG. 1 is a front, left, and bottom perspective view of a handheld device embodying the new design;

FIG. 2 is a rear, right, and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures are shown for the purpose of illustrating portions of the handheld device and/or environmental matter and form no part of the claimed design. The

(Continued)

dot-dash broken lines define the bounds of the claimed design and form no part thereof.

1 Claim, 8 Drawing Sheets
